CLAIM

The ornamental design for a cable management member, as shown and described.

DESCRIPTION

FIG. 1 is a bottom rear perspective view of a cable management member showing our new design;

FIG. 2 is a bottom view thereof;

FIG. 3 is a top view thereof;

FIG. 4 is a left side view thereof;

FIG. 5 is a right side view thereof;

FIG. 6 is a front view thereof;

FIG. 7 is a rear view thereof;

FIG. 8 is a front view of the cable management member in an environment in which it may be used;

FIG. 9 is a right side view thereof; and,

FIG. 10 is a rear view thereof.

The dashed broken lines in the figures show portions of the cable management member or environment that form no part of the claimed design.

The shade lines in the figures show contour and not surface ornamentation.

The dot-dash broken lines in the figures show boundaries that form no part of the claimed design.

1 Claim, 7 Drawing Sheets
